UNITED STATES PATENT OFFICE.

ARTHUR F. GIRNDT, OF BELLVILLE, TEXAS.

DESIGN FOR A CUTICLE IMPLEMENT.

46,636.

Specification for Design.

Patented Nov. 10, 1914.

Application filed July 29, 1914. Serial No. 853,960. Term of patent 14 years.

To all whom it may concern:

Be it known that I, ARTHUR F. GIRNDT, a citizen of the United States, residing at Bellville, in the county of Austin and State of Texas, have invented a new, original, and ornamental Design for Cuticle Implements, of which the following is a specification, reference being had to the accompanying drawing, forming a part thereof.

Figure 1 is a perspective view of a cuticle implement illustrating my design, looking

at one side thereof; and Fig. 2 is a perspective view looking at the other side of the implement shown in Fig. 1.

I claim:

The ornamental design for a cuticle implement, as shown.

ARTHUR F. GIRNDT.
